UNITED STATES PATENT OFFICE.

GEORGE D. HUNTER, OF BLOOMINGTON, INDIANA.

BOILER ATTACHMENT.

Application filed October 31, 1919. Serial No. 334,892.

To all whom it may concern:

Be it known that I, GEORGE D. HUNTER, a citizen of the United States, residing at Bloomington, in the county of Monroe and ⁶ State of Indiana, have invented certain new and useful Improvements in Boiler Attachments, of which the following is a specification.

The invention relates to improvements in ¹⁰ steam boilers.

It is an object of the invention to provide a steam boiler of the vertical type with means to prevent excessive heating of the cone sheet of the boiler, and to confine the ¹⁵ heat within the boiler smoke box below the water line of the boiler.

It is a further object of the invention to provide an attachment for boilers in which the heat is not only confined within the ²⁰ smoke box below the water level of the boiler but to also control the area of the air passage through the smoke box to cause a highly favorable operating condition in the boiler and economize in the use of fuel.

²⁵ With this conception in mind the invention comprises an attachment adapted to be placed in the smoke box of a boiler and consisting of a depending tube extending well down toward the top of the boiler flues and ³⁰ at this lower end spaced a regulated distance from a baffle plate either seated upon the flue sheet or suspended from the tube.

The tube confines the heat within the ³⁵ smoke box below the water line and prevents excessive heating of the cone sheet while the baffle enables an equal amount of air to pass through all of the flues to cause a proper combustion of the fuel and an even burning of the same within the fire box. The distance between the lower edge of the tube and the baffle may be regulated, and the area of this space should preferably be about equal to the combined area of all of the ⁴⁰ boiler tubes so as to enable a proper amount of air to pass therethrough. This regulates and controls the draft of the fire box and materially facilitates combustion of the fuel.

In the accompanying drawings I have ⁴⁵ shown the preferred embodiment of the invention.

In the drawings:—

Figure 1 is a cross sectional view, and

Fig. 2 is a view of a slightly modified form of the invention.

⁵⁰ Referring now more particularly to the drawings, the numeral 1 designates a steam

boiler which is preferably of vertical type and as is commonly used in steam channeling machines. The boiler has the usual fire box 2, and the series of vertical flues 3. It ⁶⁰ is also provided with the water chamber 4 and at its upper end with the cone sheet 5. A series of stay bolts 6 are disclosed for maintaining the different parts of the boiler in position and the boiler structure per se ⁶⁵ is, of course, old and well known, and constitutes no part of this invention.

At its upper end the boiler is provided with a smoke box 7 spaced from the outer walls of the boiler and fastened in position ⁷⁰ by means of the stay bolts 6. Positioned over the cone sheet 5 of the boiler is a cast iron ring 8 to which is attached a hood 9 carrying a smoke stack 10, a suitable exhaust pipe 11 leading from the engine cylinders ⁷⁵ or elsewhere discharging into the smoke stack.

In boilers of this character it is highly desirable to confine the heat below the top of the water line of the boiler to prevent ⁸⁰ overheating and destruction of the cone sheet. To accomplish this I dispose within the smoke box 7 a tube member 13, of substantially circular formation having an offset flange 14^a by which the tube is seated upon the top of the boiler. This tube depends well within the smoke box and as disclosed in Figure 1 serves to confine or retain the heat within the smoke box below ⁸⁵ the water line as indicated by the reference character X, and to prevent excessive heat from destroying the cone sheet. The tube may be composed of any suitable material, preferably metal, and while the structure herein shown consists of a tubular member ⁹⁰ it is, of course, manifest that the tube may take other formations should this be desirable.

Spaced from the tube 13 and seated upon the top of the boiler flues is a baffle plate ¹⁰⁰ 14 having depending legs or projections 15 seated upon the edges of the large center flue 17 of the boiler and providing openings 18 between these legs or projections to allow a small portion of heated air to pass out from large center flue under the baffle plate. The baffle plate is of a material width and extends over a number of the flues, being spaced from the upper edge of the flues to provide an opening for the passage of the ¹⁰⁵ air passing through the fire box and the flues. The width of the space between the

upper edge of the flues and the lower surface of the baffle is about equal to the total area of those flues covered by the baffle. It will be observed that the baffle is spaced 5 a slight distance from the lower edge of the depending tube 13 and the heated air passing through the flues takes the course indicated by arrows, passing through the area designated by the character $\bar{Y}$, which is 10 the space between the lower edge of the tube 13 and the surface of the baffle directly into the open interior of the tube and then out through the smoke stack.

By positioning the baffle plate over the 15 flues, as indicated, as much air is caused to pass through the extreme outer flues as passes through the inner flues thereby causing a uniform burning of the coal on the grate and producing a very natural and 20 even draft, this manifestly materially increasing the efficiency of the furnace.

A very important feature of the present invention resides in the width of the space 25 between the lower edge of the tube 13 and the surface of the baffle 14, which width as above described defines an area which is approximately equal to the combined area 30 of all of the flues. This governs the amount of air that can pass through the fire box and serves to economize in the use of fuel, especially with forced draft boilers. The 35 width of this space may be so regulated as to always properly control the quantity of air that should pass through the boiler to the end that the greatest possible economy be provided in the use of fuel consistent with a successful operation of the plant.

In the modified form of the invention as disclosed in Figure 2 I have shown the 40 baffle plate 14 as being suspended from the tube 13 by means of the hooked or bolted member 19, having threaded end portions adapted to receive the nuts 20 for supporting this plate. The invention prefer-

ably takes this form when a boiler is 45 encountered having no large central flue 17, but the objects of the baffle and the tube 13 are the same in this instance as have been pointed out in the description of the embodiment of the invention disclosed in 50 Figure 1.

Having thus described the invention what I claim is:—

1. A boiler of the character described having a plurality of vertical flues, a tube 55 disposed within said boiler and above said flues, a baffle below said tube and spaced therefrom, the total of the circumferential area between said baffle and said flues being 60 an area substantially equal to the cross sectional area of all of said flues covered by the baffle.

2. A boiler of the character described having a plurality of vertical flues, a tube positioned above said flues, a baffle below 65 the tube and overlying a number of the flues, the circumferential area of the space between the baffle and said flues being substantially equal to the combined cross sectional area of all of said flues covered by 70 the baffle.

3. A steam boiler having a plurality of flues and a water chamber, said boiler being provided with a smoke box, a tube disposed within the smoke box and extending below 75 the water line of the boiler for discharging the intensely heated gases from within the smoke box at a point substantially below said water line, a baffle spaced from the lower edge of the tube and adapted to project over at least one row of the flues, the said baffle being spaced from the upper edges of the flues covered thereby for the purpose described.

In testimony whereof I affix my signature.

GEORGE D. HUNTER.
